UNITED STATES PATENT OFFICE.

HERMANN GRUSON, OF BUCKAU, NEAR MAGDEBURG, AND MAX SCHUMANN,
OF MAGDEBURG, PRUSSIA, GERMANY.

ARMOR-PLATED GUN-CARRIAGE.

SPECIFICATION forming part of Letters Patent No. 295,246, dated March 18, 1884.

Application filed April 19, 1883. (No model.) Patented in Belgium February 28, 1883, No. 60,476; in England March 10, 1883, No. 1,288; in Italy May 16, 1883, XXX, 424, and in France July 6, 1883, No. 154,131.

To all whom it may concern:

Be it known that we, HERMANN GRUSON, of Buckau, near Magdeburg, Prussia, German Empire, and MAX SCHUMANN, of Magdeburg, 5 Prussia, have invented certain new and useful Improvements in and relating to Armor-Plated Gun-Carriages, of which the following is a specification.

Our invention relates to armor-plated gun-carriages having minimum embrasures and capable of being rotated when desired.

The accompanying drawings illustrate various modes of constructing the said gun-carriages in accordance with our invention.

15 In Figures 1 and 1^a, A represents a gun resting by means of its trunnions on a cross-head, B, which, together with the said gun, can be raised or lowered at will by means of a hydraulic piston, C, which is directly connected to the cross-head B. In its vertical movement the gun A will bear against the upper or lower edge of the embrasure in such a manner that on the movement being continued the gun will turn upon its trunnions, and thus the desired elevation for firing 25 will be obtained. The cross-head B slides upon strong guide-bars D, which are firmly secured to the armored shield or cupola E above and to a strong casting, F, below. 30 These guides neutralize the effect of the recoil of the gun. The casting F rests on a circular piece provided with rollers, which permit the gun-carriage to be easily turned, together with the armored shield, upon the vertical axis by one man by means of the rod K.

To insure accuracy of aim, it is of importance that the gun-carriage shall stand firm while the gun is being fired. This result is obtained by depressing the lower roller-track, 40 H, until the armored shield E rests upon the front armored shield, G. The roller-track H is for this purpose made to fit like a ring or sleeve upon the external surface of the hydraulic cylinder, so that it is free to move vertically thereon, and rests by means of two shoulders upon the bearing N, which is fitted to one extremity of the lever P. This lever turns upon the fulcrum O, and carries a counter-weight, Q, which approximately counter-

balances the gun-carriage in such a manner 50 that by bearing upon the lever P one man can easily raise the entire mechanism while another man turns the same by means of the rod K. The gun is thus brought to the required elevation by raising or lowering the piston C, while the lateral adjustment of the gun is effected by turning the entire gun-carriage, after first slightly raising the roller-track H for this purpose, by means of the lever P. The piston C moves up and down in the fluid-receptacle C', 60 and the latter is connected by a pipe, x, to a second fluid-receptacle, T'. This second receptacle is provided with a piston, T, having a weight, w, attached to and superimposed above it. Upon the upper surface is attached a chain or rope, v, moving over pulleys v' and v'', and attached to a winch, L, having a worm-screw, L', and a handle to operate the described mechanism. If the crank of the hand-winches be turned, the gun will be raised, for the 65 weight w, bearing on the piston T, and consequently on the fluid in the receptacle T', drives the said fluid through the pipe x and into the fluid-receptacle C', which will raise the piston C, and consequently the gun A. 75

The principal advantages of the construction above described consist, therefore, in the reduction of the power required for handling the gun as effected by the combination of a shield with the gun-carriage. This arrangement can be adapted to all descriptions of guns, and particularly to mortars. As the trunnions are frequently too weak to properly withstand a recoil, an accurately fitting cover or strengthening-piece is fitted upon the 85 rectangular shoulders of the said trunnions, which cover extends outward in the form of a ring of sufficient resisting capacity, and incloses the trunnions. The mode of attaching the cover or piece is shown in Fig. 2. 90

The above-described construction is designed to facilitate the turning and raising of the gun-carriage; but in that shown in Figs. 3 and 4 an additional object is gained. The gun in this case is designed to serve as a protection against an attack on the fortified place, and consequently must be made inaccessible to the enemy's fire—that is to say, so that it

can be raised above the parapet or shield only at the desired moment and its fire be directed against the storming parties.

- G represents the front shield, E the shield-cover, A the gun, and D the gun-carriage proper, which rests upon a hydraulic piston, C, in the cylinder C', which communicates with a cylinder, T', whose piston T is weighted to obtain the necessary pressure whereby the gun can be raised, and can be lowered by winding up a chain with the winch L and raising the said piston and weight, as described with reference to Fig. 1. The front shield on the side that is situated away from the enemy is provided with a recess into which the front part of the gun-barrel can be lowered. The gun rests upon trunnions in the ordinary manner; but the embrasure can be very small, because it is close to the trunnions and takes part in the horizontal movement. When the gun is to be fired, the gun-carriage is first raised, and then by means of the rods K the mouth of the gun is directed toward the enemy, the piston C serving as a pivot.
- Fig. 4 shows a modification of this construction in which, instead of employing the communicating hydraulic cylinders, the raising of the piston C is effected by means of chains, which pass over rollers or pulleys and are loaded with a weight, Q. In other respects the arrangement is the same.

We claim—

1. The armor-plated gun-carriage adapted to be raised by hydraulic pressure and to be lowered by a winch, as described, and provided with a piston, C, to serve as a pivot-point for rotating the gun-carriage, and to rest upon the fluid of the cylinder C' when the said carriage is elevated. 35

2. In combination with the armor-plated gun-carriage adapted to be raised by hydraulic pressure, as described, a lowering device consisting of a winch, L L', having a cord, v, moving over pulleys v' and v", for raising the weight w and withdrawing the hydraulic pressure and permitting the gun-carriage to descend, substantially as described. 40 45

3. The combination of the armor-plated shield having a minimum embrasure, as described, with a gun-carriage adapted to be elevated and supported by a piston, C, and to be rotated in a horizontal plane with the piston C as a pivot-point, or upon the roller-track, when the carriage has been slightly raised, in combination with the cylinder C', the connecting-pipe x, the cylinder T', piston T, and the superimposed weight w, controlled by a winch, substantially as set forth. 50 55
